UNITED STATES PATENT OFFICE.

JAMES E. SKIFF, OF EAST ORANGE, NEW JERSEY, ASSIGNOR TO RICE & HOCHSTER, OF NEW YORK, N. Y., A COPARTNERSHIP.

DESIGN FOR A BARRETTE.

41,360.

Specification for Design.

Patented May 9, 1911.

Application filed August 17, 1910. Serial No. 577,724. Term of patent $3\frac{1}{2}$ years.

To all whom it may concern:

Be it known that I, JAMES E. SKIFF, a citizen of the United States, residing at East Orange, State of New Jersey, have invented a new, original, and ornamental Design for Barrettes, of which the following is a specification, reference being had to the accompanying drawings, forming part thereof.

Figure 1 is an elevation of the barrette showing the exposed face of the same when in use. Fig. 2 is a perspective view of the back of the barrette.

The upper edge α has a central concave curve joined to convex curves extending therefrom to the upper corners of the bar-

rette; the lower edge β has a central convex curve joined to concave curves extending therefrom to the lower corners; the upper and lower corners being connected together by concave curves c, c . The body of the barrette is shown open or cutaway, the boundary lines of said opening generally conforming to the outer boundary lines.

I claim—

The ornamental design for a barrette as shown and described.

JAMES E. SKIFF.
